LOCOMOTIVE STOKER

Edwin Archer Turner, New York, N. Y., assignor,
by mesne assignments, to The Standard Stoker
Company, Inc., New York, N. Y., a corporation

Application August 3, 1934, Serial No. 738,167
Renewed October 4, 1938

5 Claims. (Cl. 110—104)

This invention relates generally to stokers for locomotives and the like and more particularly it appertains to that class known as inside feed stokers which convey the fuel to a point within the firebox where pressure fluid blasts act against the fuel to spread it over the firebed.

It is the principal object to provide an improved simplified and more compact stoker of the class described having all the advantages of both 10 inside and outside feed stokers and a minimum number of the disadvantages of either class.

Other objects reside in the arrangement and relation of the stoker parts with the firebox and in the particular shape of the discharge elbow, as 15 will appear in the following description taken in connection with the accompanying drawings, in which,

Fig. 1 is a central vertical longitudinal sectional view through the forward portion of a 20 tender and the rearward portion of a locomotive with the stoking device of the invention shown therein in similar section;

Fig. 2 is a fragmentary plan view of the structure shown in Fig. 1, with some parts broken away, 25 and with the firebox backhead shown in section;

Fig. 3 is a rear elevation of the backhead of the locomotive above the cab;

Fig. 4 is a rear elevation of the backhead of Fig. 1 with the stoker parts shown in cross section taken on the plane of the rear surface of the backhead; and

Fig. 5 is a sectional view on the line 5—5 of Fig. 1.

On the drawings the locomotive 10 is shown with an underframe 11, a firebox 12, and a cab 13. The firebox has a backhead 14 formed of the inner and outer sheets 15, 16 and the foundation or mud ring 17 which, as is well known, corresponds to the ground plan of the firebox. 35 Centrally of the backhead 14, the rear leg of the foundation ring is provided with an integral up-standing arch 18 positioned between the firebox sheets 15, 16 thus forming an elongated opening 19 extending above and below the cab deck or floor 20.

Rearward of the locomotive 10, the tender is indicated as a whole at 21. It is of ordinary construction having the underframe 22, the fuel bunker 23 and the apertured floor 24 which carries the usual slide plates 25. These plates, as is well understood, control the passage of fuel from the bunker 23 into the trough 26 of the stoking device S which is of improved construction and now will be described.

It includes the rearward conduit section 27, of

which the trough 26 is a part, rigidly mounted on the tender underframe 22 in any suitable manner; the forward conduit or inclined riser section 28 rigidly fixed to the foundation ring by the brackets 29 and the bolts 30, 31, as best shown in Fig. 4; and the telescopic intermediate section 32. The rearward part 33 of the intermediate conduit is universally connected at 34 to the front end of the rearward conduit section 27 and the forward part 35 of the intermediate section is similarly 10 universally connected at 36 to the forward conduit section 28. This latter section may be supported from the backhead 14 by the bracket 37 forming a seat for the feet 38 cast integral with the conduit.

Fuel is conveyed through the conduit sections by a sectional conveyor screw comprising the sections 39, 40, and 41 rotatably mounted in the conduit sections 27, 32, and 28 respectively. The adjacent ends of the screw sections are universally 20 coupled together as at 42 and 43 within the vicinity of the universal connections 34 and 36 of the conduits. Any suitable mechanism may be employed for driving the conveyor screw preferably from its rearward end.

From the description of the conduit and conveyor screw sections it will be understood that the stoker provides for the necessary articulation between the locomotive and the tender.

The invention resides particularly in the construction of the forward or inclined conduit section 28 and in its relation with the firebox 12 and associated parts as will now be fully described.

In carrying out the stated objects of the invention it is important to position the inclined conduit section 28 in the lower portion of the backhead opening 19 closely adjacent the foundation ring 17. This is desirable to avoid cab intrusion. When in this location the conduit section inclines forwardly and upwardly from beneath the cab deck 20 to a point within the firebox 12 above the grates 12a. With the deck 20 disposed relatively close to the underframe 11 as shown the inclined conduit section 28 passes through the plane of the deck close to the backhead 14. It 40 therefore protrudes slightly into the cab 13 as best shown in Figs. 1 and 3 but the amount of intrusion is not objectionable because it is not sufficient to constitute an obstruction. In those instances where the deck is disposed higher above the underframe, the inclined conduit may be positioned so that no part of it will extend into the cab.

The discharge mouth of the inclined conduit 28 is constructed in the form of a separable upwardly

opening elbow or discharge member 45 approximately triangular in shape at its outlet end. One side of the triangular outlet end is disposed parallel to the inner firebox sheet 15 and preferably in the same upstanding plane. The other sides extend forwardly to meet the rounded corner 43 the radius of which is greater than the radius of the oppositely disposed rounded corners 47, 48. As the elbow 45 extends rearwardly its shape changes gradually to a circular form corresponding to the shape of the rear portion of the inclined conduit.

A circular collar 49 at the inlet end of the elbow forms a seat 50 receiving the forward end of the rearward portion of the inclined conduit 28. Tap bolts 51 are employed to maintain these parts in operative relation. The forward screw section 41 terminates adjacent the inlet end of the elbow 45 so as not to interfere with removal or replacement of the elbow and further to cause the fuel to form into a stream filling the elbow. As the fuel rises in the elbow it is turned upwardly into the zone of action of pressure fluid jets discharging from the jet openings 52 in the distributor head 53 mounted at the rearward wall or flat side of the elbow. Bolts 54 engaging registering flanges 55, 56 of the distributor head and elbow respectively secure the head in operative position to the elbow.

The outlet end of the elbow is partially surrounded by the firing table 57 supported by the ledge 58 on the elbow and also by the lugs 59. Bolts 60 secure the lugs 59 to registering lugs 61 of the elbow 45 to fasten the firing table 57 to the elbow. Upstanding protecting grates 62 positioned approximately vertically between the table and the firebox grates and extending around the elbow to the backhead 14 protect the inclined conduit from the heat of the fire and provide the apertures 63 for introducing air over the firebed to promote combustion. This air may be drawn in through the opening 64 in the firebox grate beneath the elbow 45 or through that portion of the opening 19 below the cab deck 20.

That portion of the opening 19 above the cab deck 20 is provided with a covering comprising the separate plate-like sections 65, 66, and 67. Opposite to the upper boundary portion of the opening 19, the covering is apertured at 68 in the plate section 65 to provide an opening through which fuel may be hand fired or access may be had to the interior of the firebox. This aperture or hand firing opening 68 is closed by the usual form of "Butterfly" firedoor 69. An upstanding ledge 70 on the plate section 66 engages the lower edge portion of the firedoor to act as a stop therefor against outward pressure caused by broken flues or other boiler explosions.

Another aperture in the cover plate provided at 71 in the plate section 66 forms an opening through which may be introduced the pressure fluid supply lines 72 leading from the manifold 73 to the distributor head 53. The manifold 73 may be secured to the cover plate section 67 below the firedoor 69. Pressure fluid is supplied to the manifold through the supply line 74 and, as is well known in the art, the valves 75 of the manifold may be regulated to control the pressure fluid propelling jets.

Directly below the manifold 73 the cover plate section 67 is cut away to fit around that portion of the inclined conduit section 28 which enters the elongated opening above the cab deck 20. The bottom edge of the plate 67 contacts the

deck 20 thereby forming with the other cover plate sections together with the firedoor a covering for that portion of the opening 19 above the deck 20, with the exception of the small aperture 71. The covering is secured to the backhead by any suitable number of studs or bolts as at 76.

A floor plate 77 is fitted in the opening 19 between its sides and between the cover plate section 66 and the elbow 45 and firing table 57. This floor plate 77 extends forwardly from the cover plate section 66 adjacent the bottom of the firedoor through the plane of the backhead inner sheet 15 thereby forming a floor over which fuel may be hand fired. A depending wall 78 extending transversely across the front end of the floor plate 77 straddles the distributor head 53. This wall 78 extends vertically between the rear wall of the elbow 45 and the floor plate 77 and transversely between the sides of the opening 19 to form a closure for the space at the sides of the distributor head between the elbow and the floor plate. Hence the floor plate and its depending wall form, with the associated parts, a closure preventing air from passing over the top of the elbow and the floor plate constitutes a protecting shield for the distributor head and the pressure fluid supply lines.

Reinforcing flanges or ribs 80 extend along the sides of the floor plate 77 which as shown 30 is secured to the cover plate section 66 by the tap bolts 81 although it may be formed integral therewith.

In operation fuel from the bunker 23 passes into the trough 26 from which it is conveyed 35 forwardly by the conveyor screw sections 39, 40, 41 to the discharge elbow 45 where the fuel forms a stream filling the elbow and is urged upwardly therein by pressure of the advancing fuel from the conveyor screw. As the fuel rises in the elbow 40 the gradually changing shape thereof from the circular intake opening to the triangular outlet opening causes the fuel stream to spread rearwardly and laterally and rise evenly in front of and at the sides of the distributor head 53. The 45 under side of this head is V-shaped to assist in laterally spreading the fuel stream and to offer a minimum of resistance to its upward movement. As the fuel rises above the elbow it is swept across the firing table 57 and evenly over 50 the grate 12a by the radially directed pressure fluid blast discharged from the jet openings 52. The head 53 extends into the elbow 45 a distance sufficient to permit arranging the jet openings 55 approximately parallel to the backhead to project fuel to the rear corners of the firebox.

Should the conveyor organization of the stoker become inoperative fuel can be hand fired over the floor plate 77 and deposited on the elbow 60 and the firing table from which the pressure fluid blasts will spread the fuel over the firebed. The floor plate will shield the distributor head and the supply lines and also prevent fuel from being wasted by dropping down through the lower portion of the opening 19.

From the foregoing it will be seen that the stoker described has the advantages of distribution from a point within the firebox yet occupies a minimum of space therein, while at the same 70 time it embodies the advantage of outside feed stokers of delivering the fuel to the propelling blasts with a minimum of degradation of the lumps, yet does not protrude to an objectionable 75

extent into the cab nor employ sharp turns at the bends in the conduit system.

I claim:

1. In combination, a locomotive having a firebox with a backhead therein and a cab rearward of said backhead provided with a floor, said backhead being provided with a vertically elongated firing opening extending above and below said floor, an inclined stoker conduit extending from below the floor through the lower portion of said opening to a point within the firebox and opening upwardly therein, a distributor head mounted at the upper end of said conduit in a position to act on the fuel as it emerges therefrom, pressure fluid supply lines connected with said head extending rearward therefrom, a covering for that portion of the firing opening above said cab floor, said covering being apertured opposite the upper portion of the firing opening to provide an opening for hand firing of fuel, a firedoor for said last named opening, that portion of said covering adjacent the lower end of said firedoor being provided with an upstanding ridge for restraining the firedoor against boiler explosions and having an aperture below the firedoor for receiving the pressure fluid supply lines to said distributor head, a plate extending forwardly from said covering and being disposed between the sides of the elongated firing opening, said plate having near its forward side downwardly extending wall portions straddling the distributor head and forming a continuation of the rear wall of the conduit mouth, and a downward extending flange at its rear side arranged to receive means for securing said plate to said covering, said plate forming a floor portion for said hand firing opening and a protecting cover for said distributor head and pressure fluid supply lines.

2. In combination, a locomotive having a firebox with a backhead therein and a cab rearward of said backhead provided with a floor, said backhead being provided with a vertically elongated firing opening extending above and below said floor, an inclined stoker conduit extending from below the floor through the lower portion of said opening to a point within the firebox and opening upwardly therein, a distributor head mounted at the upper end of said conduit in a position to act on the fuel as it emerges therefrom, pressure fluid supply lines connected with said head extending rearward therefrom, a covering for that portion of the firing opening above said cab floor, said covering being apertured opposite the upper portion of the firing opening to provide an opening for hand firing of fuel, a firedoor for said last named opening, the forward end of said conduit terminating in an elbow member having bolting flanges extending rearwardly from the rear wall of the conduit mouth between the walls of the firing opening, a firing table mounted on the elbow from which the distributor head discharges the fuel as it rises from the elbow, said firing table provided with bolting flanges which extend rearward of the distributor and register with the rearward extending flanges of the elbow, means for bolting said elbow and firing table flanges together, a plate extending forwardly from said covering and being disposed between the sides of the firing opening, said plate having near its forward side downwardly extending wall portions straddling the distributor head and forming a continuation of the rear wall of the conduit mouth and protecting said bolting means from the heat rays of the fire, said plate extending rearward to the covering and forming a floor for the hand

firing opening and a protecting cover for said distributor and fluid pressure supply lines.

3. In combination, a locomotive having a firebox provided with a backhead and a cab rearward of said backhead provided with a floor, said backhead being provided with a vertically elongated firing opening extending above and below said floor, an inclined stoker conduit extending from beneath said floor through the lower portion of said opening to a point within the firebox, said stoker conduit being provided within said firebox with an upwardly directed fuel discharge mouth terminating in an approximately horizontal plane, a distributor head mounted at the upper end of said conduit adjacent the rear side thereof and extending above the aforesaid horizontal terminal plane of said discharge mouth and being disposed in a position to act on the fuel as it emerges therefrom, pressure fluid supply lines connected with said head and extending rearwardly therefrom, a plate above said distributor head extending transversely between the sides of the elongated firing opening and between the respective upper and lower ends of said sides, the portion of said elongated firing opening above said plate being arranged for manual introduction of fuel into the firebox, said plate forming a protecting cover for said distributor head and pressure fluid supply lines and having near its forward side a downward extending wall portion which straddles said distributor head and terminates at its lower portions in the aforesaid horizontal terminal plane of said discharge mouth.

4. In combination, a locomotive having a firebox provided with a backhead and a cab rearward of said backhead provided with a floor, said backhead being provided with a vertically elongated firing opening extending above and below said floor, an inclined stoker conduit extending from beneath said floor through the lower portion of said opening to a point within the firebox, said stoker conduit being provided within said firebox with an upwardly directed fuel discharge mouth terminating in an approximately horizontal plane, a distributor head mounted at the upper end of said conduit adjacent the rear side thereof and extending above the aforesaid horizontal terminal plane of said discharge mouth and being disposed in a position to act on the fuel as it emerges therefrom, pressure fluid supply lines connected with said head and extending rearwardly therefrom, a covering for that portion of the firing opening above said cab floor, said covering being apertured opposite the upper portion of the firing opening to provide an opening for manual introduction of fuel into the firebox, a firedoor for said last named opening, an aperture in said covering below said firedoor for receiving the pressure fluid supply lines to said distributor head, a plate above said distributor head extending transversely between the sides of the elongated firing opening below the level of said first named aperture and above the level of said second named aperture, said plate forming a protecting cover for said distributor head and pressure fluid supply lines and having near its forward side a downward extending wall portion which straddles said distributor head and terminates at its lower portions in the aforesaid horizontal terminal plane of said discharge mouth.

5. In a firebox having grates for supporting a firebed, a stoker for supplying fuel to said grates comprising, in combination, a conduit having an upturned elbow portion provided with a delivery mouth terminating above the level of said grates,

5 a conveyor screw rotatably mounted in said conduit and terminating adjacent the bend of said upturned elbow portion for urging fuel therethrough, the length of said upturned elbow portion through which fuel is urged by said conveyor screw being approximately equal to the greatest dimension across said delivery mouth, a distributor arranged to issue blasts of pressure fluid across the delivery mouth of said upturned elbow portion for projecting fuel over the grates, said delivery mouth being formed by straight side portions which converge toward each other, an end

portion extending transversely of said firebox, and arcuate portions joining adjacent ends of said side and end portions, said distributor being positioned along said end portion and arranged to direct blasts of pressure fluid toward the converging side portions and the connecting arcuate portion therebetween, the foremost portion of said distributor terminating rearward of the rearmost end of the upper edge of said straight side portions. 5

10 E. ARCHER TURNER.
